UNITED STATES PATENT OFFICE.

F GORDON COBB, OF GREENVILLE, SOUTH CAROLINA.

PICKER-STICK CHECK.

1,277,863.

Specification of Letters Patent.

Patented Sept. 3, 1918.

Application filed April 17, 1918. Serial No. 229,024.

To all whom it may concern:

Be it known that I, F GORDON COBB, a citizen of the United States of America, and a resident of Greenville, county of 5 Greenville, State of South Carolina, have invented certain new and useful Improvements in Picker-Stick Checks, of which the following is a full and clear specification.

This invention has relation to that type 10 of picker-stick checks in which an endless, flexible, leather or other band is arranged to encircle the path of the picker-stick and automatic means is provided to cause the band to intermittently creep or rotate to 15 thus present new surfaces to the action of the picker-stick with each stroke, thereby greatly prolonging the life of the band. Heretofore, this rotation or creeping of this band has been secured by intermittent grip 20 devices which, in practice, have been found to soon wear sufficiently to get out of order, and these devices have, therefore, not come into continuous use.

The object of my invention is to improve 25 this type of picker-stick by so constructing it that the use of cams and similar devices is entirely avoided, thus rendering the device thoroughly practical, durable and very easy for the loom attendant to care for, the 30 construction being such that what little wear there is comes entirely upon the band, so that by renewing the band at long intervals the check devices are maintained in an efficient condition, as more fully hereinafter 35 set forth.

In the drawing—

Figure 1 is a side elevation of so much of a loom structure as is necessary to illustrate my invention;

40 Fig. 2 is a horizontal sectional view taken on the line 2—2 of Fig. 1;

Fig. 3 is a vertical sectional view on the line 3—3 of Fig. 2.

In the drawing, *a* designates the band, 45 which is supported and guided in two guides *A* and *B*, the picker-stick reciprocating as usual within the band and in a path parallel to the guides. The guides are hung from the lay structure in any suitable manner.

50 Guide *B* simply supports and guides the band without any clamping action or with comparatively little clamping action. It consists of plate *c* having its lower edge turned outwardly and upwardly to form a 55 channel *d* in which the lower edge of the band rests and freely slides.

Guide *A* consists of a vertical plate *e* whose ends *g* are turned outwardly to form a support for a friction-block *h* which presses against the outer face of the band 60 and forces it against the outer face of the guide plate *e*, the means for thus frictionally forcing the block *h* against the band consisting of a flat spring *i* mounted in the ends of the arms *g* and carrying a pressure pin *j* 65 bearing with a spring action against the outer face of the block *h*. The inner end of the pin *j* is desirably provided with a rounded head *k* which bears against a leather insert *l* in the friction block, and for the 70 purpose of decreasing or increasing the friction upon the band at will, the pin *j* is threaded and provided with a pair of nuts *m* to clamp the spring *i*.

The diameter of the loop or band being, 75 as usual, shorter than the stroke of the picker-stick, the band will be bodily drawn back and forth as the picker-stick vibrates, the frictional drag (exerted mostly by the guide, *A*, which exerts a greater degree of 80 friction than the guide *B*) being sufficient to noiselessly retard and check the stick. During the working stroke of the picker-stick, the blow is, as is well-known, sharp and powerful, so that in making this working 85 stroke the band is moved bodily the full length of its stroke; that is, is drawn through both guides approximately the same distance, so that on this working stroke there is very little, if any, tendency to creep or 90 rotate. On the reverse, non-working stroke, however, the movement of the picker-stick is, as is well known, a slower and less powerful stroke, being more in the nature of a push than a blow. By reason of this slower and 95 less powerful movement of the picker-stick, the band will be drawn a farther distance out of the free guide *B* than out of the friction guide *A*, and this will result in a rotating or creeping action of the band toward 100 the friction guide, as shown by the arrow in Fig. 2. The differential friction-drag action on the two sides of the band is essential, therefore, in this embodiment of the invention.

105 Many actual tests in working looms have shown that the relation of the vertical stop edges of the two guides must be varied to get the best results, by reason not only of the slight differences in the strokes of different picker-sticks, but also because of certain differences in the strength of the blows, as 110

well as in the varying thicknesses, pliability at the laps of the bands, etc. To obtain this relative adjustability, I make at least one of the guides horizontally adjustable in any 5 suitable manner, preferably by providing the plate *c* with a longitudinal slot *o* and passing the fastening belt *p* therethrough. I preferably also make the guide plate *e* shorter than the guide plate *c*, in order to 10 get the proper degree of drag at one side and the proper guiding and supporting function at the opposite side, the free guide *B* being relied upon more than the other guide for supporting the strap in its horizontal position. It will be understood that 15 in calling the guide *B* a free guide, I do not mean by this that the band is not subjected to any friction in passing back and forth in this guide, for, as a matter of fact, I have 20 found in practice that, in order to steady this side of the band and keep it from flopping and jumping about, it is desirable to provide a slight friction in this guide *B*. The length of this guide *B* alone will sufficiently 25 create the necessary friction, but, in addition to this, I find it desirable to extend the rounded head of the belt *p* into the channel *d* in position where the band will rub against it in sliding back and forth and thus 30 slightly increase the friction.

It will be understood that my invention is not confined to the specific features of construction shown and described, since it is obvious that many changes may be made 35 in the manner of supporting and guiding the band.

The nature and scope of the invention having been thus indicated and its preferred embodiment having been specifically 40 described, what is claimed as new is:

1. In a picker check device, an endless check loop and two guides supporting the same at opposite sides of the path of movement of the picker-stick, means being provided whereby one of these guides exerts constantly a greater slip-permitting friction drag on the band than the other, whereby the mere vibration of the picker-stick will cause the band to creep or rotate.

2. In a picker check device, an endless check loop and two guides supporting the same at opposite sides of the path of movement of the picker-stick, means being provided whereby one of these guides exerts constantly a greater slip-permitting friction drag on the band than the other, whereby the mere vibration of the picker-stick will cause the band to creep or rotate, means being provided also whereby one of the guides 55 is rendered horizontally adjustable endwise.

3. In a picker check device, an endless check loop and two guides supporting the same at opposite sides of the path of movement of the picker-stick, means being provided whereby one of these guides exerts

constantly a greater slip-permitting friction drag on the band than the other, whereby the mere vibration of the picker-stick will cause the band to creep or rotate, means being provided also for endwisely adjusting 70 the guide exerting the less friction drag.

4. In a picker check device, an endless check loop and two guides supporting the same at opposite sides of the path of movement of the picker-stick, means being provided whereby one of these guides exerts constantly a greater slip-permitting friction drag on the band than the other, whereby the mere vibration of the picker-stick will cause the band to creep or rotate, the guide 80 exerting the less friction being longer than the other guide, and means being provided whereby this longer guide is rendered endwisely adjustable.

5. In a loom in which the picker-stick is 85 vibrated more powerfully on one stroke than on the other, the combination of a check-strap encircling the picker-stick and having a diameter less than the stroke of the picker-stick, and means for supporting and guiding the check-strap, these means embodying devices for constantly applying a slip-permitting friction drag to the check-strap and for causing the check-strap to rotate or creep under the direct blows of the picker- 95 stick.

6. In a loom in which the picker-stick is vibrated more powerfully on its working stroke than on the return stroke, the combination of a check-strap encircling the 100 picker-stick and having a diameter less than the stroke of the picker-stick, and means for supporting and guiding the check-strap at each side of the path of movement of the picker-stick, the supporting and guiding means at one side constantly exerting a greater degree of slip-permitting friction-drag on the strap than the supporting and guiding means at the other side, whereby the strap will have imparted to it on the working stroke of the picker-stick a body movement while on its non-working stroke the side of the strap that has the greater degree of friction-drag will be held substantially 105 against movement while the other side of the strap will be freely drawn out of the supporting and guiding means to thereby cause the strap to intermittently rotate.

7. In a loom in which the picker-stick is vibrated more powerfully on its working stroke than on the return stroke, the combination of a check-strap encircling the picker-stick and having a diameter less than the stroke of the picker-stick, and means guiding the check-strap at each side of the path of movement of the picker-stick, the guiding means at one side being constructed to constantly exert a slip-permitting drag sufficient to prevent a body movement of the strap on the non-working stroke of the 115 120 125 130

picker-stick but permitting a movement of the strap therethrough upon the working stroke of the picker-stick, whereby the strap will be given a step-by-step movement.

- 5 8. In a loom in which the picker-stick is vibrated more powerfully on its working stroke than on the return stroke, the combination of a check-strap encircling the picker-stick and having a diameter less than 10 the stroke of the picker-stick, and means for guiding the check-strap at each side of

the path of movement of the picker-stick, and for exerting constantly a slip-permitting friction-drag on the strap, the drag-producing means at one side being constructed to permit a different degree of rotative movement on the working and non-working strokes of the picker-stick. 15

In testimony whereof I hereunto affix my signature.

F GORDON COBB.
